Inventor
James J. Ferrer:

by *A. Blawie son*

Attorney.

UNITED STATES PATENT OFFICE.

JAMES J. FERRER, OF HARRIS, ALABAMA.

FENCE.

No. 800,283.

Specification of Letters Patent.

Patented Sept. 26, 1905.

Application filed May 25, 1905. Serial No. 262,257.

To all whom it may concern:

Be it known that I, JAMES J. FERRER, a citizen of the United States, residing at Harris, in the county of Barbour and State of Alabama, have invented certain new and useful Improvements in Fences; and I do declare the following to be a full, clear, and exact description of the invention, such as will enable others skilled in the art to which it appertains to make and use the same.

This invention relates to improvements in wire fences.

The object of the invention is to provide a fence of this character having metallic posts adapted to be driven into the ground and provided with wire-attaching devices adapted to be applied to certain of said posts and wire attaching and supporting devices adapted to be applied to certain other of said posts, thereby forming a strong and durable fence.

A further object is to provide a fence-wire-attaching device for the posts of the fence which may be secured to said posts at any desired position thereon, thus permitting any desired number of fence-wires to be used, means being provided whereby the fence-wires are clamped or secured to the post simultaneously with the securing of the attaching device, said attaching devices and the wire-engaging surface of the post being so formed as to prevent cutting of the fence-wires when clamped to the post.

With these and other objects in view the invention consists of certain novel features of construction, combination, and arrangement of parts, as will be hereinafter described and claimed.

In the accompanying drawings, Figure 1 is a perspective view of a section of fence constructed in accordance with the invention, showing two posts, one of which has applied thereto wire-attaching devices and the other of which has applied thereto wire attaching and supporting devices. Fig. 2 is a side view of a fence-post having applied thereto devices for attaching the fence-wires. Fig. 3 is a horizontal sectional view of the same. Fig. 4 is a side view of a post having applied thereto wire attaching and supporting devices, and Fig. 5 is a horizontal sectional view of the same.

Referring more particularly to the drawings, 1 denotes a post of the fence which is preferably formed of a rectangular metal bar, one end of which is beveled or inclined, forming an edge to facilitate the driving of the

post into the ground. Adjacent to the upper end of the post are formed laterally-projecting lugs 2, with which are adapted to be connected the upper ends of the brace-bars 3, by which said posts are braced after being driven into the ground.

In the construction of the fence I employ two forms of wire-attaching devices, one form of which is applied to every fourth post, while the other form is applied to the three intermediate posts. The form of the attaching device which is applied to the three intermediate posts is shown in Figs. 2 and 3 of the drawings and consists of a strip or plate of metal 4, bent upon itself in the form of a loop and has formed in its opposite ends bolt-holes 5, which when said ends are brought together after being looped around the post are brought into alinement, and through the same are inserted clamping-bolts 6. Upon the clamping-bolts 6 are adapted to be screwed a nut 7, which when screwed up upon said bolt will clamp the sides of the strip into engagement with the sides of the post. In the opposite sides of the strip 4 adjacent to the loop or doubled end of the same are formed wire-receiving notches 8, which terminate in the form of circular eyes or apertures 9, through which the fence-wires are adapted to pass. The position of the eyes or apertures 9 is such with respect to the front or forward edge of the post that when the ends of the strip 4 are drawn together by the clamping-bolt and nut the wire passing through said eyes or apertures will be drawn around the forward edge of the post and securely clamped thereto. The edges of the eyes or apertures 9 are rounded, as is also the front edge of the post, whereby when the wire is clamped against the post the same will not be cut or broken.

On every fourth post of the fence is employed combined attaching and supporting devices by which the line-wires are not only held in tight engagement with the post, but are also rigidly supported against possibility of slipping, these devices being clearly shown in Figs. 4 and 5 of the drawings. The attaching and supporting devices consist of a bail-shaped plate or strip 10, in the opposite sides of which, adjacent to the ends thereof, are formed wire-engaging notches 12. These notches 12 terminate in alined eyes or apertures 13, through which are adapted to pass the line-wires of the fence when the device is applied to the post. In the loop or doubled end of the strip 10 is formed an aperture 14,

through which is adapted to be passed a set-screw 15, said set-screw being adapted to be screwed through nuts 16, arranged within the looped portion of the strip 10. The inner end of 5 the set-screw 15 is pointed and when screwed into engagement with the rear side of the post will be forced into the same, thereby rigidly holding the attaching device 10 against slipping upon the post. When the set-screw 10 15 is thus screwed into engagement with the rear side of the post, the line-wires of the fence passing through the eyes 13 in the opposite ends of the strip will be drawn tightly around the forward rounded edge of the post, 15 thus securely attaching the wire thereto. The edges of the eyes or apertures 13 are rounded to prevent the cutting of the line-wires when the same are drawn thereby into engagement with the forward edge of the post. 20 By providing a combined attaching and supporting device for each fourth post of the fence the line-wires will be firmly supported or held in place against slipping on the post, the attaching devices for the intermediate 25 posts being supported by the line-wires of the fence, as well as by the clamping-bolts 6, which are applied thereto. In a fence constructed as herein shown and described any form of line-wires may be employed, and a 30 strong durable fence will be formed thereby.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of 40 this invention.

Having thus described my invention, what I claim as new, and desire to secure by Letters Patent, is—

1. A fence of the character described having 45 posts arranged at suitable intervals, line-wires secured to said posts, attaching devices clamped to certain of said posts to attach said line-wires to said posts, attaching and supporting devices arranged on certain other of 50 said posts, and each comprising a bail-shaped plate adapted to engage the sides of a post, means whereby the fence-wire is engaged with the ends of said plate, and a set-screw to be passed through said plate and into engagement with the rear side of the post, thereby supporting said attaching devices and bind-

ing the line-wire to the post, substantially as described.

2. A fence of the character described comprising posts arranged at suitable intervals, 60 said posts having a rounded outer edge, line-wires adapted to be secured to said posts, line-wire-attaching devices arranged on certain of said posts, said attaching devices consisting of metallic strips having wire-receiving notches 65 and adapted to be looped around said posts, clamping-bolts passed through the ends of said strips, nuts screwed onto said bolts to draw said ends of the strips together and the line-wires into close engagement with the 70 post, line-wire attaching and supporting devices arranged on certain other of said posts, said devices consisting of bail-shaped plates or strips adapted to engage the sides of said posts, said strips having near their ends wire-receiving notches, and means whereby said devices are rigidly secured to a post to attach the line-wires thereto and to support the same at the desired position, substantially as described. 75

3. A fence of the character described comprising posts arranged at suitable intervals, said posts having a rounded outer edge, line-wires adapted to be secured to said posts, line-wire-attaching devices arranged on certain of 80 said posts, said attaching devices consisting of metallic strips having wire-receiving notches and adapted to be looped around said posts, clamping-bolts passed through the ends of said strips, nuts screwed onto said bolts to 85 draw said ends of the strips together and the line-wires into close engagement with the post, line-wire attaching and supporting devices arranged on certain other of said posts, said devices consisting of bail-shaped plates or strips adapted to engage the sides of said 90 posts, said strips having near their ends wire-receiving notches, a nut arranged in the looped end of said strip, a pointed set-screw adapted to be passed through an aperture in said looped 95 end and screwed through said nut and into engagement with the rear side of the post, thereby attaching the line-wire and supporting the device against slipping on the post, substantially as described. 100

In testimony whereof I have hereunto set my hand in presence of two subscribing witnesses.

JAMES J. FERRER.
